Alex A. Rommel, 2265 Poppy, Fresno, Calif.

Filed Mar. 6, 1961, Ser. No. 64,164

Term of patent 14 years

(Cl. D71—1)

FIG. 1 is a top plan view of an airship showing my new design.

FIG. 2 is a side elevation thereof. Each side of the airship is the same in appearance as the side shown.

FIG. 3 is a bottom plan view of the airship.

The dominant features of the design reside in the portions shown in full lines.

I claim:

The ornamental design for an airship, as shown and described.
